UNITED STATES PATENT OFFICE.

LOUIS H. MCKEE, OF TRENTON, NEW JERSEY.

SCHOOL-DESK.

1,261,574.

Specification of Letters Patent.

Patented Apr. 2, 1918.

Application filed January 23, 1915. Serial No. 3,859.

To all whom it may concern:

Be it known that I, LOUIS H. MCKEE, a citizen of the United States, residing in the city of Trenton, county of Mercer, State of New Jersey, have invented a new and useful School-Desk, of which the following is a specification.

My invention consists of a school desk having its side standards formed of a double thickness of sheet metal and tongues or lips on the terminals of the double walls of said standards integral therewith, said tongues or lips comparatively approaching, and the member of the desk which is connected with said standards being formed with grooves or channels to receive said tongues or lips, and the latter being adapted to be tightened on the walls of said grooves or channels producing lightness, strength, and inexpensiveness in the construction of the same.

It consists also in forming the seat-support and the desk-top support in similar manner with similar results.

It consists also of novel means for connecting the seat with its support. It consists also of novel means for connecting the back or back rest and the desk-top with their supports respectively.

It consists also of a novel construction of the axis of the folding seat of the desk of double walls, each wall being formed of interengaging inturned and outturned lugs, there being a plurality of lugs on the double walls on each side of the axis, as will be hereinafter described.

It consists of novel means for supporting the shelf of the desk in position, and adapting the desk proper to be cleaned and the dirt, etc., removed therethrough.

It consists also in providing the desk top with a novel rack for pens, etc.

The invention is satisfactorily illustrated in the accompanying drawing, but the important instrumentalities thereof may be varied, as long as they are included in the scope of the claims.

Figure 1 represents a perspective view of a school desk embodying my invention. Fig. 2 represents a longitudinal vertical section thereof.

Fig. 3 represents a vertical section of a portion on the line $\alpha-\alpha$ Fig. 1, on an enlarged scale showing the locking joints of the desk top and the supporting bracket thereof. Fig. 4 represents a vertical sec-

tion of a modification of the features shown in Fig. 3.

Fig. 5 represents an elevation of another modification of said locking joints.

Fig. 6 represents a horizontal section on the line $y-y$ Fig. 1.

Fig. 7 represents a perspective view of a portion of the shelf of the desk top.

Fig. 8 represents a longitudinal vertical section of another portion of the desk on an enlarged scale.

Fig. 9 represents a rear view of a portion thereof.

Figs. 10 and 11 represent side elevations of the joint portions of the seat of the desk.

Fig. 12 represents a vertical section on the line $z-z$ Fig. 2 on an enlarged scale.

Fig. 13 represents a vertical section of a portion on the line $y-y$ Fig. 8. Fig. 14 represents a diagrammatic view of a prepared blank from which certain members of the desk are formed.

Fig. 15 represents a horizontal section of a portion on the line $a-a$ Fig. 8.

Similar numerals of reference indicate corresponding parts in the figures.

Referring to the drawings.

1 designates the side standards of a school desk, 2 the legs thereof, 3 the supports at the top for the back 4 of the desk, and 5 the arm on which the supports 6 for the folding seat 7 are pivotally-mounted.

Each of the standards, legs, top supports, and arms is formed of a piece of sheet metal made from the blank shown in Fig. 14, which is folded on itself on the median line $b-b$, and finally shaped, the opposed edges of which come together, being seamed or otherwise connected forming said members hollow of a double thickness of walls, and rendering them light, strong and durable and inexpensive.

8 designates side brackets which support the desk top 9, it being noticed that said brackets are each formed of a piece of sheet metal made from the blanks shown in the upper part of said Fig. 14, which are brought together and their opposed edges seamed or secured forming said brackets hollow of a double thickness of walls and rendering them light, strong, durable and inexpensive. The upper ends of said brackets 8 are formed with vertically projecting lips 10 which are adapted to enter the grooves 11 in the under side of the desk top 9, and are

spread apart by the inserted rods 12, as wedges which form dovetailed joints for said top and brackets, and so firmly connect the same, as most plainly shown in Fig. 3. 5 Another form of such joints is shown in Figs. 4 and 5, where portions of the lips 13 are bulged apart as at 14, they being somewhat resilient so as to tighten against the walls of the groove 15 in the desk top which 10 they enter and slide through, and so are compressed against said walls and held firmly thereon.

The rear of the standards 1 are formed with pressed out sockets 16, and the lower 15 ends of the forward portions of the brackets are formed with depending legs 17 which are adapted to enter said sockets, thus supporting said ends on the standards, it being noticed that the flanges in the front ends 20 of the brackets enter the rear ends of the contiguous portions of the tops 3 of the standards and are wedged therein similar to what is shown in Figs. 3 and 4, the brackets being furthermore secured to said 25 tops by the stirrups 18, which are riveted to and so connected with said tops and enter said brackets where they receive the transversely-extending bolts 19, which are also passed through the sides of the brackets and 30 are retained in position by the nuts 20 forming firm connections for the parts in question. As the pressed or punched out sockets 16 are integral with the rear bends of the double walled standards 1, they are strong 35 and durable and add but little expense to the desk. Then they are filled by the occupation of the legs 17 whereby they cannot be battered-in by the scholars, and the lower edges of the legs are covered and guarded 40 from contact and made inaccessible to attempt to pry under said ends and raise the legs also by the scholars.

When the riveted stirrups are removed, the legs may be raised from the sockets, and 45 thus the desk top may be displaced for purposes of repairs, replacement by a new top, packing, shipping or other purposes.

Again as said depending legs 17 are lowered into the socket 16 and rested therein they are so covered that their lower ends 50 present no raw edges, which otherwise would cut anything that comes in contact with them, this being prevented by the above construction.

55 The seat supports 6 are formed each of a piece of metal folded on itself, rendering them hollow producing a double thickness of walls which are light, strong, durable and inexpensive, they also having on their upper 60 ends flanges which are inserted in recesses or grooves in the underside of the seat 7 and wedged or otherwise tightened therein, thus forming dovetailed joints for said seat and supports which provide strong connections for the parts in question.

The upper portion of the arms 5 have segmental lugs 21 struck up thereon, the same being respectively inturned and outturned, and the rear portions of the sides of the seat supports 6 have segmental lugs 70 22 struck up thereon, centered from the bolts 23, said lugs being respectively inturned and outturned, so that the lugs of one member will enter freely the other, the adjacent ends of the arms 5 entering the adjacent ends of the supports 6, forming with said bolts 23, which pass through said arms and supports, the axis or hinge of the seat, permitting the latter to be raised and lowered, the opposite lugs being adapted to abut 80 at the terminals of the motions of the seat, the stops therefor, it being noticed that the outturned lugs on the arms 9 are shorter than those on the supports 6, thus permitting the same to turn in the latter to the required 85 extent.

Caps 24 are placed over the lugs of the supports 6 and retained by the bolts 23, as coverings and finishes for said lugs.

25 designates the shelf in the desk proper, 90 the same having on its sides the tenons 26 which enter mortises 27 in the brackets 8 of the desk-top and rest on the bases 28 which are punched out and turned down from the material of said brackets in 95 forming said mortises 27, and so provide firm enlarged or wide rests for said tenons 26 and consequently for the shelf as is evident, said shelf being held laterally in position by the opposite side brackets 8, without 100 necessarily requiring any applied fastenings.

In the shelf 25 at the sides of the tenons 26 are spaces forming the passages 32 which are within the inner sides of the brackets 8, 105 whereby dust, dirt, or other deposits may be swept through said passages, thus cleaning the interior of the desk proper.

The front of the upper portion 3 of the side standards are formed with forwardly 110 projecting lips 29 which are adapted to enter vertical grooves 30 in the rear of the back 4, and to be spread apart therein by the rod 31, thus forming a dovetailed joint for said back and standards, which firmly and 115 reliably interlock said members.

On the desk top 9 at the front thereof is the rack 33 for pens, pencils, etc., the same having on its forward end the depending flange 34 which is interposed between the 120 front edge of said top and the rear of the seat back 4, and so retained in position. While the standards and supports are made each of a single piece of metal folded on itself, they each may be made of separate 125 pieces of metal, secured together, and preserving the double walls of each part.

Attention is drawn to the fact that the seat, back and desk-top are formed of wood, and the members 3, 6, and 8 are formed of 130

metal, each of the latter being provided with a plurality of tongues that are spread apart when in the respective groove or recess of the wooden members, whereby the respective 5 wooden and metal members are firmly connected.

The tongues on the seat supports 6 are shown in dotted lines, Fig. 2, but they are similar to those shown in Figs. 3, 4, and 5. 10 On the center of the bolt between the inner walls of the axial portion of the seat support and adjacent portion of the standard on which said support is pivotally mounted is a washer 35 which serves to space said walls 15 and prevent crushing in of the several walls that form the axis of the seat-support.

Having thus described my invention what I claim as new and desire to secure by Letters Patent, is:—

20 1. In a desk, a support for the back thereof formed of double walls of sheet metal, lips on the terminals of said walls continuous of the latter and integral therewith, and projecting forwardly therefrom, said back 25 having in its rear side a groove adapted to receive said lips, the latter being adapted to be tightened in said groove.

2. In a desk, members formed of double 30 walls of sheet metal, lips on the terminals of said walls, continuous of the latter and integral therewith, and projecting therefrom, and approximately meeting, and a member of the desk adapted to be connected with said walls, said last named member 35 having a groove therein adapted to receive said lips, the latter being adapted to be tightened in said groove.

3. In a desk, a desk top, a shelf in said top, a bracket adapted to support said top,

said shelf having on its end spaced-apart 40 tenons, and said bracket having in its side mortises adapted to receive said tenons, and walls of said mortises adapted to form ledges on which said tenons are adapted to be supported. 45

4. In a desk, a desk top, a shelf in said top, a bracket adapted to support said top, said shelf having on its end spaced-apart tenons, and said bracket having in its side a mortise 50 adapted to receive said tenons, and a wall on said mortise adapted to form a ledge on which said tenons are adapted to be supported, said ledge being an integral member of the vertical side of said bracket and extending horizontally from the same. 55

5. In a desk, a table top, a bracket adapted to support said top, and a side standard, said bracket having a depending leg, and said standard having a socket in which said leg is adapted to be seated, said socket being open at the top, closed on its sides and bottom, and formed of an integral portion 60 of said standard outturned therefrom.

6. In a desk, a table top, a bracket adapted to support said top, and a side standard, said bracket having a depending leg, and said standard having a socket in which said leg is adapted to be seated, the upper portion 65 of said bracket being secured firmly to said standard, said socket being open at the top, closed on its sides and bottom, and formed of an integral portion of said standard outturned therefrom. 70
